CLAIM

The ornamental design for a coin depositing and dispensing apparatus, as shown and described.

DESCRIPTION

FIG. 1 is a perspective view of the front, top and right side of a coin depositing and dispensing apparatus showing our new design;

FIG. 2 is a perspective view of the front, top and left side thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom view thereof.

The broken lines illustrate portions of the coin depositing and dispensing apparatus that form no part of the claimed design.

1 Claim, 8 Drawing Sheets
